DESIGN FOR A WHIPPER BLADE

George L. Moeller, St. Louis, Mo.

Application March 17, 1942, Serial No. 106,224

Term of patent 7 years

To all whom it may concern:

Be it known that I, George L. Moeller, a citizen of the United States and a resident of the city of St. Louis, in the State of Missouri, have invented a new, original, and ornamental Design for a Whipper Blade, of which the following is a specification, reference being had to the accompanying drawing, forming a part thereof.

Figure 1 is a top plan view of a whipper blade, showing my new design;

Figure 2 is a front elevational view;

Figure 3 is an end elevational view thereof;

Figure 4 is a horizontal sectional view on the line 4—4 of Figure 2; and

Figure 5 is a horizontal sectional view on the line 5—5 of Figure 2.

I claim:

The ornamental design for a whipper blade substantially as shown.

GEORGE L. MOELLER.
